(57) **CLAIM**

The ornamental design for a panel for an inner portion of a reusable diaper, as shown and described.

DESCRIPTION

FIG. 1 is a top plan view of an inner portion of a reusable diaper;

FIG. 2 is a bottom plan view hereof;

FIG. 3 is a left side view thereof;

FIG. 4 is a right side view thereof;

FIG. 5 is a front side view thereof; and,

FIG. 6 is a back side view thereof.

The details shown in broken lines depict environmental subject matter only and form no part of the claimed design. The sizing and dimensions of the panel for the inner portion of the reusable diaper, and/or other individual parts thereof, also form no part of the claimed design.

The claimed design is primarily the configuration of a panel for an inner portion of a reusable diaper as viewed, for example, when the reusable diaper is in a generally open position. This configuration is shown in FIG. 1 illustrating the top plan view of the panel. An opposite side of the panel forms no part of the claimed design. In FIG. 1, the heavier weight line defines part of a perimeter of the panel for the inner portion of the reusable diaper. And, the lighter weight line defines a seam where material is coupled together to form the panel for the inner portion of the reusable diaper.

Each of the panels of the inner portion of a reusable diaper are flat and level with one another.
